Attorney, Agent, or Firm—Fish & Richardson

CLAIM

The ornamental design for a Configurable, Modular Power Supply, as shown and described.

DESCRIPTION

FIG. 1 is a front and right perspective view showing our new design;

FIG. 2 is a rear and left perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof;

FIG. 8 is a left side view thereof; and,

FIG. 9 is a front and upper right perspective view thereof shown with one of the modules partially removed.

FIG. 1

FIG. 2

FIG. 3

FIG. 4

FIG. 7

FIG. 8

FIG. 5

FIG. 6

FIG. 9
